UNITED STATES PATENT OFFICE.

WILLIAM F. KIESEL, JR., OF ALTOONA, PENNSYLVANIA.

LOCOMOTIVE BOILER.

Application filed December 12, 1924. Serial No. 755,562.

This invention relates to boilers and more particularly to a steam dome arrangement for use in conjunction with locomotive type boilers.

It has been found that where the maximum overall height of a boiler is limited, as in railway practice, that the use of the ordinary type of steam dome results in restricting the steam space and the water surface, which may be conveniently termed the "steam disengaging surface" so that the throttle valve, which is located in the steam dome, may entrain a considerable quantity of water due to violent disengaging of the steam, the disadvantages of which are well-known. It is an object of this invention to provide in a locomotive type boiler, an improved steam dome construction which provides an increased "steam disengaging surface," an increased steam space and which may be constructed without the use of stays.

In the accompanying drawings and following specification there is disclosed by way of example, only, a single embodiment of the invention with the understanding that various changes may be made in the form, size, proportion and arrangement of the various parts by those skilled in the art without departing from the spirit of the invention as more particularly pointed out in the appended claims.

In said drawings,

Figure 1 is a partial longitudinal vertical section through a steam boiler constructed according to this invention, and

Figure 2 is a transverse vertical section on line 2-2 of Figure 1.

In modern railway practice it is necessary to provide locomotives of great power and in order to supply sufficient steam, boilers of large steaming capacity are necessary. The size of the boiler shells which must be cylindrical, in good practice, to eliminate staying is limited by two factors, first, the height of the running gear and frame, and second, the height of tunnels, bridges, viaducts, etc., beneath which the locomotives must pass. It is the usual practice to provide at the top of the main barrel-sheet a steam dome within which is arranged the throttle valve leading to the dry pipe. The purpose of this dome is, of course, to maintain the throttle valve at as great a distance as possible above the surface of the water in the boiler to prevent entraining water with

the steam. The top of the dome is therefore made as high as allowable by the second limitation mentioned above, but since the dome is usually of small size and the main barrel-sheet of substantially the same diameter as the remaining portions of the barrel, the steam space above the water is quite limited, in fact in some of the largest locomotives the water level is only about nine inches below the inside of the top of the barrel-sheet. This materially reduces the area of the "steam disengaging surface" resulting in violent boiling, priming and foaming and increasing the tendency to entrain water into the throttle valve. The present invention accomplishes the desired results by providing an enlarged, main barrel-sheet, circular in cross-section, tangential at the bottom with the remaining barrel-sheets and reaching at the top to the maximum height permissible for clearance in tunnels, etc., as mentioned.

Referring to the drawings, 10 indicates the forward portion of the barrel of a locomotive boiler, connected by means of the main barrel-sheet 11 with the fire-box section 12 here shown as of the Belpaire type. The forward portion of the barrel 10 is circular in cross-section as is usual and therefore the forward end 13 of the portion 11 is also circular to be readily fitted thereto. The enlarged central portion of the main barrel-sheet 11 is circular in cross-section as best shown in Figure 2 and forms, at the bottom, a substantially straight surface 90 with the section 10 and the lower portion of the fire-box section 12 to which it is joined at the section 14 by a lap joint. The section 11 is however eccentrically located in respect to the other barrel sections owing to its larger diameter but the bottom is like a standard boiler. With this construction the central line of the boiler will be indicated by the dot and dash line shown in Figure 1. Connecting the large central portion of the main barrel-sheet 11 and the smaller circle of the section 13 is the tapered section 15 always circular in cross-section on section lines at right angles to the main central line of the boiler to eliminate the need of staying. The reduced rear section 14 is connected to the main portion by a similar tapered section 16 and the portion 14 is shaped to conform to the forward end of the fire-box construction which in the

Belpaire type disclosed is provided with the hips 17. In case the boiler is used with a wagon-top type of fire-box the portion 14 will be circular in cross-section owing to the 5 circular roof on this type of fire-box. As in the section 15, the section 16 is so shaped as to be circular in cross-section at all sections arranged at right angles to the longitudinal center line of the boiler.

10 In order that the main barrel-sheet may be shaped as shown it is necessary to form it in two parts which can each be readily fitted in a press for shaping, the two parts being joined by butt joints 18 along the 15 sides. The opening 19 in the top of the main barrel-sheet, which corresponds to the opening in the usual dome, is reinforced by the internal ring member 20. The joints 18 of the barrel-sheet are reinforced by the 20 inner and outer plates 21 and 22.

It will be seen that this construction provides in effect a combination barrel-sheet and steam dome which is equivalent to extending the dome on a standard boiler to 25 form a part of the main barrel-sheet. At the same time all cross-sections at right angles to the longitudinal central line of the boiler are circular to avoid the necessity of applying stays. Increased steam space and 30 a larger "steam disengaging surface" are

thus provided without increasing the over-all height of the boiler.

Having thus described the invention, what is claimed as new and desired to be secured by U. S. Letters Patent is:

35 1. In a locomotive type boiler, a shell comprising two end sections, a circular section intermediate and joining said end sections being of greater cross-sectional area than said end sections and joined to the end sections so that the lowest portions of all sections form a substantially straight surface, whereby increased steam space is provided.

40 2. In a locomotive type boiler, in combination, a fire-box section, a barrel section, a combination main barrel-sheet and dome section interposed between said first mentioned sections, said combination main barrel-sheet and dome section being larger 45 in diameter than the barrel and fire-box sections, tangential thereto at the bottom and having reduced ends for connection to adjacent sections, to thus provide increased steam space and "steam disengaging surface".

50 55 In testimony whereof I hereunto affix my signature.

WILLIAM F. KIESEL, JR.
